UNITED STATES PATENT OFFICE

2,652,664

OPERATOR-CONTROLLED GRINDING MACHINE WITH OPTICAL COMPARATOR

James A. Allan, Springfield, Vt., and Francis C. Savage, Columbia, Conn., assignors to Jones & Lamson Machine Company, Springfield, Vt., a corporation of Vermont

Application April 18, 1952, Serial No. 283,066

4 Claims. (Cl. 51—165)

1

This invention relates to machines for accurate generations of desired contours and has for one object a provision for operator control of the feed of the tool, such as a grinding wheel, in accordance with a desired contour and in connection with an enlarged image of such contour or of successively presented portions thereof.

A further object is to provide for indirect projection of the work contour image from a position well spaced from the contact between the grinding wheel and the work so that the grinding may be accomplished wet, thereby providing for maximum grinding speed with good conditioning of the ground surface and avoiding formation of dry detritus or dust likely to interfere with or damage lenses or other parts of the optical system employed for projection of the contour image.

Such indirect projection of contour image further makes possible the employment of optical control in situations such as the generation of internal surface contours where direct projection would be impossible.

For a complete understanding of this invention reference may be had to the accompanying drawings in which

Figure 1 is a somewhat diagrammatic front elevation of a grinding machine embodying the invention.

Figure 2 is a top plan view of the same.

Figure 3 is a left side elevation of the same partly broken away and in section.

Figures 4 and 5 are detail sectional views on lines 4—4 and 5—5, respectively, of Figure 1.

Figure 6 is a view similar to a portion of Figure 1, but showing a modification.

Figure 7 is a detail sectional view on line 7—7 of Figure 6.

Figure 8 is a fragmentary view showing a portion of the projection screen with the projected image of a reticle and tolerance circles.

Figure 9 is a side elevation of a wheel truing device in use.

Figure 10 is a detail sectional view on line 10—10 of Figure 9.

Figures 11 and 12 are detail sectional views on lines 11—11 and 12—12, respectively, of Figure 10.

Figure 13 is a fragmentary view partly broken away and in section and similar to a portion of Figures 1 and 6, but showing the grinding of internal work.

Figure 14 is a view similar to Figure 1, but showing a further modification.

Figures 15 and 16 are detail sectional views on

lines 15—15 and 16—16, respectively, of Figure 14.

Figure 17 is a view similar to a portion of Figure 13, but showing a further modification.

Figure 18 is a view similar to a portion of Figure 1, but showing a modified control mechanism.

Figure 19 is a diagram of the control mechanism of Figure 18.

Referring first to Figure 1 of the drawings, at 1 is indicated a machine base having a vertical standard 2 on which a slide 4 is mounted in suitable ways 3 for vertical motion. This slide 4, as shown, has oppositely directed portions 5 and 6, the portion 5 being formed as a holder for a work piece 7 which is to be ground in its upper face to a desired contour. This work piece 7 is adjustably supported by the work support, and for thus purpose it is shown as resting upon a pair of independently adjustable supporting screws 8 and being clamped within a slot 9 (see Figure 2) in the work support by means of clamp screws 10. This slide 4 is shown as provided with a nut 11 threaded upon a vertically arranged screw 12 journaled in the support 2 and carrying at its lower end a spiral gear 15 with which meshes a spiral gear 16 carried by a horizontal shaft 17 provided with an actuating hand wheel 18 on its forward end. The support 2 is also mounted on the bed 1 for horizontal motion, being formed as a slide provided with a depending internally threaded boss 20 through which passes a horizontal screw 21 carrying at one end a spiral gear 22 which meshes with a spiral gear 23 on a horizontal shaft 24 shown as arranged parallel to the shaft 17 and having a hand wheel 25 at its forward end.

It will be apparent that by rotating the hand wheel 18, the carriage 4 may be raised or lowered, and by rotating the hand wheel 25, the support 2 can be moved horizontally. Thus the work support 5 is capable of being moved in either of two right angularly related directions in a common plane and the work piece may be caused to traverse past a grinding wheel 30 in the same plane, and mounted for rotation on a spindle journaled in a supporting carriage slide 31 which is mounted for vertical adjustment on a slide-way 32. A vertically positioned adjusting screw 33 carried by the member 32, and engaging a suitable internally threaded nut on the slide 31, provides for vertical adjustment of the grinding wheel. The slide 31 also carries a motor 35 which is connected to rotate the grinding wheel 30 through the pulleys 36 and 37 and the connecting belt 38.

The slideway 32, as shown, is carried by a sliding carriage 46 mounted for motion horizontally transverse to the plane of motion of the work holder. It may be oscillated in this transverse plane when desired to provide a latterly flat ground face and for this purpose it may be provided with a slot 41 (see Figure 5) in which rides a crank pin 42 on a disk 43 carried by a shaft 44 journaled in any suitable manner vertically in a supporting stand 45 carried by the bed 1 and mounted for adjustment toward and from the carriage support 2. The crank disk 43 may be rotated as by a motor 50 carried by the stand 45 and having on its armature a worm engaging a worm wheel 51 carried by the shaft 44.

The stand 45 may be adjusted horizontally toward and from the work holder by rotation of a hand wheel 52 carried by a horizontal shaft 53 having thereon a pinion 54 engaging the teeth of a rack bar 55 carried by the stand.

By suitable adjustment of the various parts, the grinding wheel 30 may be brought into proper relation to the work piece 7 and may be caused to traverse the work piece generating a desired contour, by suitable manipulation of the hand wheels 18 and 25, to keep the images on the screen in proper relation as one is caused to traverse the other. In order, however, to produce a desired contour with high accuracy, optical means are provided spaced from the engagement between the grinding wheel and the work for projecting an enlarged image of a target onto a suitable screen in cooperative relation to a reference line on the screen. Where the work piece is moved to provide the feed between the work piece and the grinding wheel, as in Figure 1, this projected target 60 may be carried by the arm 6 and have an end portion simulating the contour of the grinding wheel 30.

This target 60 is adjustably secured to the arm 6 so that its projected image may be brought into proper relation to a contour marking on the screen 61 when the grinding wheel is in corresponding relation to the work piece. As shown best in Figure 3, the optical system comprises a lamp housing 62 and a suitable lens system comprising a condensing lens 63 the light beam from a lamp in the housing 62 being projected past the upper end of the target 60 and being focused by a lens system so as to cast an image onto the mirror 65 which is reflected back magnified against the screen 61. This image of the target is shown in dot and dash lines in Figure 1 on the screen in successive positions as the work piece is moved past the grinding wheel and the target image is moved along the screen. As shown in this figure, the desired contour of the work piece is shown in magnified relation on the screen by the line 67, there being lines 68 and 69 parallel thereto which are spaced therefrom proper distances to show tolerance limits. Thus as the work piece is passed beneath the grinding wheel in contact therewith and the target image is moved along the screen, the work piece and target may be raised and lowered in accordance with the contour of the line 67 so that the image of the target remains within the tolerance limit lines 68 and 69 throughout the full extent of the grinding motion.

It will be noted that the target is spaced a substantial distance from the work piece where grinding is being effected, so that it is quite feasible to apply coolant to the grinding wheel and work as through the pipe 10 (Figures 4 and 9) so that grinding may be accomplished at maximum speed

and with the ground surface maintained in the best possible condition without overheating and without the formation of dry detritus or dust which might find its way to the lenses or other parts of the optical system, resulting in damage thereto.

Since the work piece as shown in Figures 1 and 2 is a flat plate, it is desirable to oscillate the wheel support so as to prevent the formation of a dished portion between the side faces of the work so that the grinding takes place uniformly across its full thickness. This, of course, may be accomplished by driving the motor 50.

Where the entire contour to be ground is relatively small, the magnified image of the contour can be projected on a screen of reasonable dimensions, but in cases where the contour is large, such projection would result in the requirement of a screen of excessive dimensions. In such a case a different form of target may be used, as illustrated, for example, in Figure 6, together with a different type of image carried by the screen and to which the projected image is to be properly related during the grinding operation. As shown in Figure 6, the target, instead of being a representation of the grinding wheel contour in cross section, comprises a reticle 75 having the desired work piece contour marked thereon, as the line 74. This reticle is transparent and is mounted for suitable adjustment by clamps 76 and 77 which engage a base member 78 which carries the reticle. Various adjusting screws 79 and 80 may be employed to facilitate proper positioning of the contour line on the reticle with relation to the motion of the work piece during the grinding operation. With this arrangement a small part only of the contour line 74 is in the path of the projected beam of light at any one time, as shown, for example, in Figure 8, and cooperating with this projected portion of the contour line are shown three circles 85, 86, and 87, the circle 85 being positioned intermediate between the tolerance circles 86 and 87, an arcuate portion of the circle 85 representing a magnified portion of the active contour of the grinding wheel. With this arrangement it is only necessary to so control the vertical and horizontal motions of the work holder that the portions of the contour line 74 successively projected on the screen remain tangent to the circle 85 or within the tolerance limits shown by the circles 86 and 87.

It is, however, unnecessary that the movable holder carry the work rather than the grinding wheel. Figure 14 shows the grinding wheel carried by the arm 5a and the work piece 7a carried by a holder 45a which may be mounted for motion transverse to the plane of the work piece between the dotted line positions of Figure 16 in order to traverse the entire thickness of the work piece by the grinding wheel in a manner similar to that shown in connection with Figure 1. The work may be oscillated laterally of the plane of motion of the wheel and the target by the crank mechanism actuated by rotation of the drive shaft 89 as shown in Figure 14. This figure also shows the use of a reticle as a target, the projected portion of the contour line of the reticle being related to a central U-shaped line 98 similar to the enlarged projected image of the wheel contour and which is positioned between the parallel tolerance lines 91 and 92. It will be understood, however, that where the work piece is small, the reverse arrangement of target and screen image shown in Figure 1 could be em-

ployed, the target representing a replica of the grinding edge of the grinding wheel, and the indication on the screen being that of the desired contour to an enlarged scale.

In order that the grinding wheel may be caused to accurately grind the work piece to the desired contour, it is important that it be kept true to a shape corresponding to its representation on the screen, either as an enlarged projected image of the target or the enlarged contour indication marked upon the screen. To this end a wheel truing device has been illustrated at 100 carried by an arm 101 (see Figures 9 to 12) which is fulcrumed on an axis 102 adjustably positioned to pass through the grinding wheel at 103 as shown in Figure 12, so that by rocking the truing device about its pivot axis 102, the grinding surface may be trued to the desired semicylindrical contour. The pivot 102 is carried by a block 1020 which may be adjusted inwardly as the grinding wheel wears, a spring 106 serving to press the block 1020 inwardly as far as is permitted by the nut 105 threaded on the screw 104. This truing device may be swung out of the way when not desired, being carried by an arm 107 fulcrumed at 108 to a bracket 109 carried by the wheel-carrying slide so that it may be swung between the operative position shown in Figures 9, 10 and 11 and the inoperative position shown in Figures 4 and 5.

The provision of a target remote from the contact between the grinding wheel and the work makes it possible also to generate contours which cannot be directly projected at the contact between the wheel and the work piece, as, for example, internal contours as shown in Figure 13. In such cases the work piece 7b will be carried by a spindle 115 mounted for rotation about an axis lying substantially in the plane of relative motion between the grinding wheel and work holder having a suitable chuck 116 for supporting the work piece 7b and suitable means such as a motor arranged within a housing 117 may be employed to rotate the work piece. It will be understood that for such an internal contour, a corresponding internal contour will be shown on the screen.

A further internal contoured work piece is shown in Figure 17 in which the work piece instead of being cylindrical is a plate. This, however, may be mounted similarly to the work piece shown in Figure 1. With this arrangement the use of circles such as 85, 86 and 88 shown in Figure 8 to represent the wheel contours is highly desirable since these will be effective for both the upper and lower edges of the contoured work piece.

In some cases it may be desired to control the two directions of motion between the grinding wheel and the work piece to produce a desired contour by a single controlling member instead of by separate manipulation of the two hand wheels such as 18 and 25. Such an arrangement is illustrated somewhat diagrammatically in Figures 18 and 19. The horizontal movements of the target and either the work piece or the grinding wheel, depending upon which of these is mounted to move with the target, is produced by a power mechanism shown as a hydraulic differential cylinder 125 having a piston 126 therein connected through a piston rod 127 to a lug 128 projecting downwardly from the carriage 2. Similarly the vertical motion of the carriage 4 may be produced by a similar differential hydraulic cylinder 130 in which a piston 131 is

slidable, being connected to the vertical slide 4 through a piston rod 132. The piston sides of both of these cylinders are connected to the pressure line 133 from a hydraulic pump 134 (Figure 19) which takes its supply from a tank 135. A valve 136 controls the supply and discharge of fluid from the head end of the cylinder 125, and a valve 137 similarly controls the supply and discharge from the head end of the cylinder 130 as through the pipes 140, 141, and the pistons 142 and 143 of these valves are connected through the rods 144 and 145 and the pivoted links 146 and 147 with a control lever 148 pivoted at 149 eccentric to the connection 150 of the links 146 and 147 thereto. By angular adjustment of the control arm 148 about its pivot 149 the relative sizes of the valve openings to the head ends of the two hydraulic cylinders may be adjusted relatively, to thereby adjust the amounts of fluid entering these head ends, and by turning this control member 148, the relative rates of motion vertically and horizontally may be adjusted and regulated in accordance with the contour which it is desired to cut by the grinding wheel in the work piece.

By moving the control member 148 to a different angular position, the supply to the pipes 140 and 141 may be shut off, whereupon the pressures exerted on the inner faces of the pistons 142 and 143 will return these pistons to the head ends of the cylinders, the target and the part movable therewith then being in starting position. As shown in Figure 18, this member 148 may be connected to a hand wheel 160 by which its angular positioning may be facilitated and a pointer 161 thereon may aid in showing the position of adjustment for any given slope of the cut.

From the foregoing description of certain embodiments of this invention it will be evident to those skilled in the art that further various changes and modifications may be made without departing from its spirit or scope.

We claim:

1. In combination, a work support, a grinding wheel support, a rotary grinding wheel carried by said grinding wheel support, means for rotating said grinding wheel, means mounting one of said supports for motion in a plane in either or both of a pair of angularly related directions to cause said grinding wheel to generate a contour on a work piece carried by said work support, means supplying coolant to said wheel and work piece, a target remote from the engagement between said wheel and work and connected to said movable support to partake of the movement of said movable support, a screen, an optical system arranged to project a magnified image of at least a portion of said target onto said screen transverse to said plane, said screen having an image thereon of the same scale as said target image, power-operated means for moving said support and target in each of said angularly related directions, and a common control means operatively connected to both said power means and actuatable to control both of said power means to move said movable support and target in selectable relative rates in each of said directions.

2. In combination, a work support, a grinding wheel support, a rotary grinding wheel carried by said grinding wheel support, means for rotating said grinding wheel, means mounting one of said supports for motion in a plane in either or both of a pair of angularly related directions to cause said grinding wheel to generate a contour on a work piece carried by said work support, means

supplying coolant to said wheel and work piece, a target remote from the engagement between said wheel and work and connected to said movable support to partake of the movement of said movable support, a screen, an optical system arranged to project a magnified image of at least a portion of said target onto said screen transverse to said plane, said screen having an image thereon of the same scale as said target image, a pair of fluid pressure motors connected to said movable support and target each arranged to move said support and target in one of said angularly related directions, a control valve for each of said valves to actuate said said motors, and a single actuator for said valves mounted for angular motion about a center and operatively connected to said valves to actuate said valves selectively and simultaneously control the directions and rate of motions of said fluid pressure motors.

3. In combination, a work support, a grinding wheel support, a rotary grinding wheel carried by said grinding wheel support, means for rotating said grinding wheel, means mounting one of said supports for motion in a plane in either or both of a pair of angularly related directions to cause said grinding wheel to generate a contour on a work piece carried by said work support, means supplying coolant to said wheel and work piece, a target remote from the engagement between said wheel and work and connected to said movable support to partake of the movement of said movable support, a screen, an optical system arranged to project a magnified image of at least a portion of said target onto said screen transverse to said plane, said screen having an image thereon of the same scale as said target image, and means for moving said movable support in said angularly related directions in a manner to cause said target image to trace said screen image and thereby control the work contour generated by said wheel, said work support having a work-carrying spindle mounted for rotation about an axis lying substantially in said plane.

4. In combination, a work support, a grinding wheel support, a rotary grinding wheel carried by said grinding wheel support, means for rotating said grinding wheel, means mounting one of said supports for motion in a plane in either or both of a pair of angularly related directions to cause said grinding wheel to generate a contour on a work piece carried by said work support, means supplying coolant to said wheel and work piece, a target remote from the engagement between said wheel and work and connected to said movable support to partake of the movement of said movable support, a screen, an optical system arranged to project a magnified image of at least a portion of said target onto said screen transverse to said plane, said screen having an image thereon of the same scale as said target image, and means for moving said movable support in said angularly related directions in a manner to cause said target image to trace said screen image and thereby control the work contour generated by said wheel, said work support having a work-carrying spindle mounted for rotation about an axis lying substantially in said plane and said screen image having an internal contour to be traced by said target.
